OPHTHALMOSCOPE

Theobald Graff, Rathenow, Germany, assignor to
 Emil Busch, Aktien-Gesellschaft, Optische-
 Industrie, Rathenow, Germany

Application July 21, 1938, Serial No. 220,553
 In Germany July 24, 1937

12 Claims. (Cl. 88—20)

My invention relates to ophthalmoscopes having self-contained illuminating means and more especially to improvements in ophthalmoscopes of the so-called "Thorner" type, known for instance from Dr. Walther Thorner's—the inventor's—own German Patent 218,227, applied for in 1909, and from British Patent 29,466 to Schulz—another German inventor—applied for in 1912.

The objects of this invention and the advantages obtained will be more fully understood by first reviewing the advantages and deficiencies characteristic of the "Thorner" ophthalmoscopes when compared with those of other ophthalmoscopes having self-contained illuminating means, known for instance from United States Patent 2,014,888 to Forshey, and with those of the oldest and simplest type of ophthalmoscopes widely known and briefly called hereinafter the "Helmholtz" ophthalmoscope, which has no self-contained illuminating means, but simply consists of a concave mirror having a central opening, and cooperating with a foreign source of light.

Because of its simplicity of construction, low price, small compass and weight and the large magnification of the funds obtained, which is magnified about fifteen times by the refracting cooperation of the patient's pupil and which is seen in its natural upright position, the Helmholtz ophthalmoscope has been, up to the present day, used by eye-specialists, more so because as a rule only eye-specialists acquire and preserve by constant practice the great manual skill required in successfully using the old Helmholtz ophthalmoscope.

As a matter of fact, known among medical practitioners, in inspecting the patient's fundus with the Helmholtz ophthalmoscope great skill and dexterity is required for so manipulating and aiming the instrument, that the beam of light which is to be directed into the patient's eye but strongly reflected in the first instance by the convex face of the pupil—the cornea—does not coincide with and does not suppress the weaker picture of the fundus composed of the more diffuse light rays reflected from the latter.

A few other drawbacks inhering to ophthalmoscopes of the old Helmholtz type consist in that their fields of vision is rather small, namely restricted practically to the size of the patient's pupil, that, on using the instrument indirectly, i. e. jointly with a condenser lens for enlarging the field of vision, the resultant picture is magnified only by 4 to 5 times, that the magnified fundus picture lies upsidedown instead in upright position, and—last not least—that also at

the said lens glaring lights and irritating reflexes are produced, which must be avoided by further concentration on the part of the observer in skillfully handling the instrument.

As well the use of direct method (without condenser) as the indirect method (with condenser) of using the ophthalmoscope was facilitated by the invention of the electric ophthalmoscope which differs from the Helmholtz ophthalmoscope with respect to the self-contained illuminating means in fixed position and being known for instance from the cited United States Patent to Forshey; yet the disturbances from that glare are unavoidable also with the use of this ophthalmoscope and they are in principal the same as with the Helmholtz ophthalmoscope.

Thorner's and his successor's improved self-illuminating ophthalmoscopes referred to above and widely used by the medical profession avoid the glaring lights reflected both from the magnifying lens used in connection with the old Helmholtz instrument and from the patient's cornea by the provision of an optical system radically different from the former, namely being enclosed in a casing or dark room and including a source of light, a concave mirror directly opposed to the patient's eye, another reflecting mirror, and an eye piece co-operatively associated with a diaphragm.

For reasons known in all details only to manufacturers of ophthalmoscopes of the Thorner type the overall length of the latter necessary for accommodating in a casing their complex optical system is rather large, approximating in practice about 200 millimeters or 8 inches; their great length causes in turn a rather long total distance of the observer's eye from the patient's eye, and this what may be called long leverage renders the handling of the instrument uncomfortable at least on examining the outer peripheral and eccentric zones of the fundus, more so since the examination is somewhat impeded by the inverted position of the retinal image and the small rate of magnification.

In spite of these and other drawbacks including their relatively high price ophthalmoscopes of the Thorner type are widely used all over the world because of the freedom from glaring lights and delusive reflections, and have been up to the present the diagnostic instrument preferred by a great many physicians and allround medical practitioners who are not eye-specialists and are not acquainted with the intricacies of ophthalmoscopes of the Helmholtz type, and who

only occasionally have to resort to diagnoses based on inspection of the patient's fundus.

The principal object of the invention is to provide a structurally improved self-illuminating 5 ophthalmoscope, wherein the various drawbacks inherent to instruments of the self and non self-illuminating types referred to above are eliminated, and which offers their advantages combined, namely: A relatively short distance—not 10 exceeding 100 millimeters—between the doctor's and the patient's eyes, a relatively large rate of magnification of the retinal image ranging above 15, absence of glaring lights and delusive reflections, the retinal image to be seen erect and in 20 natural position, namely with no left to right lateral change as with images seen in a mirror as will be explained more in detail hereinafter.

Other objects of the invention will become incidentally apparent to practitioners in this field 25 as the description proceeds.

The nature and scope of the invention are briefly outlined in the appended claims and will be more fully understood from the following specification taken together with the drawing, 25 in which

Fig. 1 is a fragmentary elevation perspective showing by way of an example an ophthalmoscope improved according to this invention.

Fig. 2 is a section vertically taken through the 30 instrument on its optical main axis.

Fig. 3 is a fragmentary side elevation of the upper section of the instrument with a protecting cover removed.

Fig. 4 is a section horizontally taken through 35 the upper section of the instrument on line 4—4 in Fig. 2 and seen from below in the direction of the arrows.

Fig. 5 is a perspective view showing in a larger scale a roof shaped prism as used for the purposes of this invention, of which the bottom and rear face through which the light rays enter and pass out respectively are the only ones which are not blackened and are marked by hatched lines.

45 The ophthalmoscope re-designed with the objects in view outlined above and shown by way of an example in the drawing comprises:

(1) A tubular casing 6 closed at the top and having two apertures or sight holes in its upper 50 section namely a front aperture 7 opposed to the patient's eye E and a rear aperture diametrically arranged to the former and facing the observer's or doctor's eye E'.

(2) Primary reflecting means in the form of 55 a mirror 8 fixed within said casing at its front aperture 7 in inclined position for reflecting light rays received from below into the patient's eye E and vice versa as indicated in Fig. 2 by dash lines i—i and dash and dot lines i'—i'.

60 (3) Secondary reflecting means comprising a roof or similar side inverting prism 10, fixed in said casing 6 at its rear aperture, in spaced relation to the mirror 8, and having blackened faces 65 except its bottom and rear face which are marked by hatched lines in Fig. 5, and a diaphragm 11 partly covering the bottom face of the prism and leaving free only a restricted area of the latter for selecting and allowing a limited portion of 70 light rays reflected from below to pass therethrough.

As indicated by dash lines in Fig. 5 the light rays selected and entering the prism in the direction of arrow r are reflected therein twice by 75 the inclined roof of the prism and pass out

through its rear face in the direction of the arrow r'.

(4) Illuminating means enclosed in the upper portion of the casing 6 which comprise:

An incandescent electric lamp 12 preferably 5 presenting a rectilinear filament (not shown), a socket 13 wherein said lamp is fixed and through which the latter is connected with an electric circuit indicated at 14; the socket 13 wholly encloses the electric lamp 12 except at its upper 10 right side where a condensing and reflecting element preferably in the form of a small concave mirror 16 is detachably fixed in such position opposed to the electric lamp 12 and the roof prism 10, that a beam of light indicated in Fig. 2 by its 15 central ray i is downwardly reflected so as to closely pass by the inner end of said blackened roof prism 10.

(5) A concave mirror 18 fixed in the lower portion of casing 6 in opposed position to said 20 illuminating and reflecting means for cooperation therewith; the distance of said lower concave mirror from said reflecting means is so chosen, that the light rays received at and reflected from the concave mirror 16 enclose a relatively small 25 angle a, substantially not exceeding 20°. This is an important feature of the instrument re-designed according to this invention, inasmuch as distortions of the fundus image are avoided by virtue of the smallness of said angle and of 30 the strictly symmetric position of the concave mirror 16 relatively to the reflecting means 8 and 10.

(6) An eye piece of the so-called "Recess" type attached to the casing 6 and comprising: A 35 primary rotatable disc 20, wherein a primary set of lenses 21, graduated as to their refracting characteristics preferably progressing from 10 to 10 diopters is fixed, a dial 22 bearing indices which is cooperatively associated with said primary disc 20 by a toothed gearing 22', a secondary rotatable disc 24 coaxially arranged to the former which is provided with indices and wherein a secondary set of lenses 25 graduated as to their refracting characteristics, preferably 40 lenses ranging from one to nine diopters, is fixed for cooperation with the said primary set of lenses 21, and a cover 26 having sight holes n, n', n'' and enclosing said discs 20, 24 and said dial 22.

The cover 26 is so designed and proportioned 45 that the dial 22 and the secondary disc 24 are accessible to the operator as seen in Fig. 1 and can be revolved independently of each other; a selected pair of lenses 21, 25 chosen with regard to anomalies or specific defects of vision 50 of the patient's eye can thus be quickly brought into line with the light rays issuing from the roof prism 10 at r' and an amply magnified image showing the illuminated section of the fundus in natural position without lateral left to right changes will be visible to the operator.

Goods results have been obtained with ophthalmoscopes re-designed according to this invention wherein the optical characteristics of the vital component parts described above were so chosen, that the magnification of the retinal picture ranged from 15 to 20.

The absence of glare and irritating reflexes in 60 the retinal image is due to the specific design 70 and light selecting arrangement of the roof prism 10 described and its cooperation with the diaphragm 11 and the other optical elements of the instrument.

No special skill is required in so holding the 75

instrument relatively to the patient's eye that the condensed beam of light produced by the illuminating means is thrown upon the fundus through an eccentric section of the patient's pupil E, say the lower half of the latter, as seen in Fig. 2 from the inner rays i--i indicated by dash lines; in this case the retinal image produced and seen by the observer will be composed exclusively of light rays which are reflected from the fundus through the upper section of the patient's eye and are selected by the roof prism 10 as seen from the light rays i'-i' indicated by dot and dash lines.

Instead of the rather costly eye piece of the Recoss type described chosen with the object of enabling the operator to compromise during the inspection with specific defects of vision of the patient's eye, another appropriate and less expensive eye piece of simpler design as known in the art may be applied to equal advantage for the purposes of this invention.

Various other changes and modifications may be conveniently made in the structural details of ophthalmoscopes of the improved design described, without substantially departing from the spirit and the salient ideas of this invention:

For instance the casing 6 of the instrument, which because of its tubular form presents a proper handle by itself, may be provided to advantage with a separate handle 36 telescopingly and detachably fitted by means of a reduced neck 36' in the lower portion of the casing 6 for frictional engagement therewith and carrying said concave mirror 18; this latter feature is advantageous because on withdrawing the handle 36, the mirror 18 and the interior of the casing 6 are accessible for inspection, cleaning, repair and kindred purposes.

The said handle 36 may be made hollow for the reception of an electric dry cell and/or for accommodating a switch for making and breaking the electric current supplied to the electric lamp 12.

The upper section of the tubular casing 6 carrying the illuminating and reflecting means including the mirror 8, the roof prism 10 and the diaphragm 11 may be made to advantage as a separate structural element in the form of a cap 46 telescopingly and detachably fixed in the casing 6 by frictional interengagement; some of the lower contour lines of said cap 46 are shown at 46' and 46" in Figs. 1 and 2. The optical characteristics of the eye piece and concave mirror are so chosen that a magnified image of the fundus is produced, the rate of magnification averaging fifteen.

Although a preferred embodiment of this invention has been illustrated and described, variations within the true spirit and scope of the same are to be determined by the appended claims.

What I claim is:

1. An ophthalmoscope comprising in combination an elongated hollow casing, one end of said casing having closely spaced front and rear walls, the closely spaced walls having optically aligned apertures, one in each wall, a concave mirror mounted in the casing remote from said end and positioned with its optical axis substantially parallel with the longitudinal axis of said casing and with its reflecting surface toward said end, a front mirror mounted in said casing adjacent the front wall aperture with its reflecting surface inclined toward said front wall aperture, a rear mirror mounted adjacent the rear wall aperture

with its reflecting means inclined toward the rear wall aperture, said front and rear wall mirrors being inclined to reflect light from the respective apertures toward the concave mirror and then from the concave mirror to the other aperture, means between the front and rear mirrors to provide a light passage to the concave mirror, and means to direct light through said passage. 5

2. An ophthalmoscope comprising in combination a substantially elongated hollow casing having closely spaced front and rear walls and having optically aligned apertures therein adjacent one end of said casing, a concave mirror mounted in said elongated casing remote from said end and positioned with its optical axis substantially parallel with the longitudinal axis of the casing, a mirror in said casing adjacent the front wall aperture having its reflecting surface inclined toward said aperture to direct images received therethrough upon said concave mirror, a reflecting prism adjacent the rear wall aperture having reflecting means inclined to said aperture to receive images from said concave mirror and direct them through the rear wall aperture, and means between the second named mirror and prism, providing a light passage to the concave mirror and arranged to direct light through said passage. 10

3. An ophthalmoscope comprising in combination an elongated hollow casing, one end of the casing having closely spaced front and rear walls, the closely spaced walls having optically aligned apertures, one in each wall, a concave mirror mounted in the casing remote from said end and positioned with its reflecting surface facing toward said end, a primary reflecting means mounted in said casing adjacent the front wall aperture with its reflecting surface inclined toward said front wall aperture, secondary reflecting means mounted adjacent the rear wall aperture with its reflecting surface inclined toward the rear wall aperture, said reflecting means being inclined to reflect light from the respective apertures toward said concave mirror and then from the concave mirror to the other aperture, 35 means between the front and rear apertures to provide a light passage to the concave mirror, and a light source arranged to direct light through said passage. 40

4. An ophthalmoscope comprising in combination an elongated hollow casing, one end of the casing having closely spaced front and rear walls with optically aligned apertures in said walls, a concave mirror mounted in the casing remote from said end and positioned with its reflecting surface toward said end, primary reflecting means mounted in said casing adjacent the front wall aperture with its reflecting surface inclined toward said front wall aperture, secondary reflecting means mounted adjacent the rear wall aperture with its reflecting surface inclined toward the rear wall aperture, said reflecting means being inclined to reflect light from the respective apertures toward said concave mirror and then from the concave mirror to the other aperture, 45 means between the front and rear apertures to provide a light passage to the concave mirror, and a light source detachably affixed to said casing and arranged to direct light through said passage. 50

5. An ophthalmoscope comprising in combination an elongated hollow casing having closely spaced front and rear walls at one end with optically aligned apertures in each wall, a concave mirror mounted in the casing remote from said

70

75

end and positioned with its reflecting surface toward said end, a primary reflecting means mounted in said casing adjacent the front wall aperture with its reflecting surface inclined toward said front wall aperture, secondary reflecting means mounted adjacent the rear wall aperture with its reflecting surface inclined toward the rear wall aperture, said reflecting means being inclined to reflect light from the respective apertures toward said concave mirror and then from the concave mirror to the other aperture, means between the front and rear apertures to provide a light passage to the concave mirror, and means to direct light through said passage, said mirror and reflecting means positioned and arranged so that the angle between received and reflected light beams does not exceed in the neighborhood of about 26°.

6. An ophthalmoscope comprising in combination a substantially elongated hollow casing having closely spaced front and rear walls and having optically aligned apertures therein closely adjacent one end of said casing, a concave mirror mounted in said casing remote from said end and positioned with its reflecting surface toward said end, a mirror in said casing adjacent the front wall aperture having its reflecting surface inclined toward said aperture to direct images received therethrough upon said concave mirror, a reflecting prism adjacent the back wall aperture having reflecting means inclined to the last mentioned aperture to receive images from said concave mirror and direct them through the rear wall aperture, means between the second mirror and prisms providing a light passage to the concave mirror, a source of light in said casing, and a mirror to direct light from said source through said passage to said concave mirror.

7. An ophthalmoscope comprising, in combination a substantially elongated hollow casing having closely spaced front and rear walls with optically aligned apertures therein closely adjacent one end of said casing, a concave mirror mounted in said elongated casing remote from said end and positioned with its optical axis substantially parallel with the longitudinal axis of the said casing, a mirror in said casing adjacent the front wall aperture having its reflecting surface inclined toward said aperture to direct images received therethrough upon said concave mirror, a reflecting prism adjacent the back wall aperture having reflecting surface inclined to the last mentioned aperture to receive images from said concave mirror and direct them through the rear wall aperture, an eye-piece optically aligned with said rear wall aperture, and means between the reflecting surface of the second mirror and prism providing a light passage to the concave mirror and to direct light through said passage, said mirrors, eye-piece, and prism so arranged that the observed image is magnified in the neighborhood of about at least fifteen times.

8. An ophthalmoscope comprising in combination an elongated hollow casing having closely spaced front and rear walls, optically aligned apertures with one in each wall, a mirror mounted in the casing remote from said end and positioned with its reflecting surface toward said end, primary reflecting means mounted in said casing with its reflecting surface inclined toward said front wall aperture, secondary reflecting means mounted in said casing with its reflecting surface inclined toward the rear wall aperture, said reflecting means being inclined to reflect

light from the respective apertures toward said first named mirror and then from the first named mirror to the other aperture, means between the front and rear apertures to provide a light passage to the concave mirror, and a light source arranged to direct light through said passage, said light source and reflecting means being so located in the casing, that the light beams directed into the observed eye and reflected from the fundus thereof pass through different parts of the pupil.

9. An ophthalmoscope comprising in combination a substantially elongated hollow casing having closely spaced front and rear walls adjacent one end of said casing, and having optically aligned apertures in said walls, a concave mirror mounted in said elongated casing remote from said end and positioned with its reflecting surface facing toward said end, primary reflecting means in said casing adjacent the front wall aperture having its reflecting surface inclined toward said aperture to direct images received therethrough upon said concave mirror, a secondary reflecting means adjacent the rear wall aperture having its reflecting surface inclined to the last mentioned aperture to receive images from said concave mirror and direct them through the rear wall aperture, means between said reflecting means, providing a light passage to the concave mirror and to direct light through said passage, and said means all positioned in a detachable end cap constituting a part of the casing.

10. An ophthalmoscope comprising in combination an elongated hollow casing one end thereof having closely spaced front and rear walls with the walls each having optically aligned apertures, a concave mirror mounted in the casing remote from said end and positioned with its reflecting surface toward said end, a primary reflecting means mounted in said casing adjacent the front wall aperture with its reflecting surface inclined toward said front wall aperture, a secondary reflecting means mounted adjacent the rear wall aperture with its reflecting surface inclined toward the rear wall aperture, said reflecting means being inclined to reflect light from the respective apertures toward said concave mirror and then from the concave mirror to the other aperture, means between the front and rear apertures to provide a light passage to the concave mirror and to direct light through said passage, and a detachable handgrip supporting said concave mirror and constituting an end portion for said casing.

11. An ophthalmoscope comprising in combination a substantially elongated hollow casing having closely spaced front and rear walls and having optically aligned apertures therein adjacent one end of said casing, a concave mirror mounted in said casing remote from said end and positioned with its reflecting surfaces toward said end, a mirror in said casing adjacent the front wall aperture having its reflecting surface inclined toward said aperture to direct images received therethrough upon said concave mirror, a reflecting prism adjacent the rear wall aperture having a reflecting surface inclined to the last mentioned aperture to receive images from said concave mirror and direct them through the rear wall aperture, means between the second mirror and prism providing a light passage to the concave mirror and to direct light through said passage, and an apertured plate supporting

- said prism in said casing and defining the limits of said passage.
12. An ophthalmoscope comprising in combination an elongated hollow casing, one end of the casing having closely spaced front and rear walls, optically aligned apertures, one in each wall, a concave mirror mounted in the casing remote from said end and positioned with its reflecting surface toward said end, a front mirror mounted in said casing adjacent the front wall aperture with its reflecting surface inclined toward said front wall aperture, a rear mirror mounted adjacent the rear wall aperture with its reflecting

means inclined toward the rear wall aperture, said front and rear wall mirrors being inclined to reflect light from the respective apertures toward the concave mirror and then from the concave mirror to the other aperture, means between 5 the front and rear mirrors to provide a light passage to the concave mirror and to direct light through the said passage, and a manually variable eyepiece carried on said casing adjacent the rear wall aperture and arranged to vary its 10 refracting characteristics.

THEOBALD GRAFF.
